UNITED STATES PATENT OFFICE

2,122,087

SEALING CONTAINER

Frank Oscar Levi Chorlton, Bury, England

Application December 5, 1934, Serial No. 756,167
In Great Britain December 14, 1933

9 Claims. (Cl. 226—68)

In the process of canning goods it is sometimes found beneficial to charge the containers in which the goods are packed and before they are sealed, with an inert or preservative gas, 5 nitrogen being, for example, employed to preserve the flavor or aroma or to enhance the keeping properties, and the object of the present invention is to provide a machine in which both the charging and sealing operations are carried out 10 expeditiously and in such manner as to effect considerable economy in the quantity of inert gas employed.

I have illustrated my invention in the accompanying drawings, in which:—

15 Fig. 1 is a side elevation partly in medial section of a machine for sealing containers in a gas other than atmospheric air,

20 Fig. 2 is a front elevation mainly in section on the line II, II of Fig. 1, in which the parts are shown to a somewhat larger scale, and in which the pump connections are indicated. The valve V and its casing are in Fig. 2 shown in section on the line III, III of Fig. 11, the section being viewed in the direction indicated by the 25 arrows on the said line.

Fig. 3 is a fragmentary portion of Fig. 2 to the same scale as Fig. 1, the view being a section on the line III, III of Fig. 11 viewed in the direction indicated by the arrows on the said 30 line of section, and

Fig. 4 is a part plan view corresponding with Fig. 3, and

Figs. 5 and 6 show a modification;

Fig. 5 being an elevation in section on the 35 line V, V of Fig. 6, and

Fig. 6 being a plan view in section on the line VI, VI of Fig. 5.

Fig. 7 is a plan view showing a further modification in which there is a plurality of auxiliary sealing chambers formed in a rotatable 40 drum.

Figs. 8 and 9 show a further modification in which there is a plurality of auxiliary sealing chambers formed in a rotatable drum;

Fig. 8 being a plan in section on the line VIII, VIII of Fig. 9,

Fig. 9 an elevation in section on the line IX, IX of Fig. 8.

Fig. 10 is a plan view, similar to Fig. 8, and 50 shows a modification in which there are two drums each having a set of auxiliary sealing chambers, the one set being employed to introduce the cans into the main sealing chamber, and the other set to withdraw them therefrom.

Figure 11 is a sectional view of the valve V and its casing v3 on the line XI, XI of Figure 3, the direction in which the section is viewed being indicated by the arrows on the line of section XI, XI.

5 A is the main frame of the machine over which is located the driving shaft B, which is driven by the pulley b1 from an electric motor or a countershaft.

The shaft B drives the seaming head c located 10 in the sealing chamber C, and also drives a vertical cam shaft D; and cams on the cam shaft control or operate, the clearing rod G, the seaming rollers c5, the shutter valve H, the auxiliary sealing chamber M, and the rising and falling 15 table P. Any suitable mechanism may be employed for this purpose in combination with the gas control means herein described. I have by way of example illustrated mechanisms for these 20 purposes which are more fully described in my concurrent application for a patent, Serial No. 756,165, the same letters of reference being employed in both specifications.

The shaft B is journalled in bearings carried 25 in the casing E and F mounted on the top of the frame A; the shaft B is connected by spiral gearing, located in the casing E, to the vertical shaft of a seaming head c, located in the sealing chamber C; the seaming rollers c5 are rendered operative to bead the lid on the can by 30 any suitable and well known mechanism, operated by a cam c1 mounted on the vertical cam shaft D; a pin roller c2 mounted on a transmission member c3 engaging a cam groove in the 35 face of the cam, the member c3 being guided in a fixed guide c4 carried from the main frame and extending into the sealing chamber C and actuating a cam mechanism enclosed in the said chamber.

A clearing rod G is operated by a cam g1 actuating a roller g2 on a transmission member g3 guided in a guide g4; one arm of a bellcrank lever g5 being connected to the transmission member g3, the other arm being connected by 45 a rod g6 to a lever g7 pivoted on links g8 carried from the casing E, the other end of the lever g7 being connected to adjustable stops g9 on the clearing rod G, the function of the rod G is to engage with the lid of any can which 50 may get jammed in the beading mechanism, and to push the can out.

The cam shaft D is driven from the shaft B, preferably by means of a worm and worm wheel and slipping clutch housed in the casing F, the 55

lower end of the shaft being supported in a foot-step bearing *d*5.

The bottom *c*15 of the sealing chamber C is provided with an opening *c*13 concentric with the centre of the beading head and the opening is controlled by a shutter valve H which is reciprocated so as alternatively to open and to close the opening *c*13; the shutter valve is operated by a cam *h*1 on the cam shaft D bearing against a roller *h*2 fixed to the end of a transmission member *h*3 guided in a guide *h*4. The member *h*3 carries a head *h*5 in which is fitted a transverse pin *h*11 having a transverse hole in which latter fits the tail end *h*10 of a lever *h*8 pivoted at *h*8' to a fixed bracket *h*7 in which the shaft D rotates freely, the upper end of the lever *h*8 is connected by a link *h*9 to a stem attached to the shutter valve H.

K is the table of the machine which in operation is fixed, but which is adjustably carried from a vertical facing on the frame A, in this table a well *k*1 is formed in which slides vertically an auxiliary sealing chamber M, the hollow cylindrical stem *m*15 of the chamber passing out through the boss at the bottom of the well of the table; the upper end of the sealing chamber is open and its top edge, in its upper position is adapted to make joint with a packing ring *m*10 carried in a groove in the bottom *c*15 of the main sealing chamber C.

Vertical reciprocating motion is imparted to the auxiliary sealing chamber M by means of a cam *m*1 mounted on the cam shaft D and engaging with a roller *m*2 on the transmission member *m*3 guided in the fixed guide *m*4; a roller *m*5 on the member *m*3 engaging the arm *m*6 of a bellcrank lever pivoted at *m*7 to the table K; the other arm *m*8 of the bellcrank lever being made jaw-shaped and being connected by two links *m*9 to a pin *m*13 fixed to the hollow stem of the chamber M, and pins passing through suitable slots in the wall of the well *k*1 of the table K.

P is a movable table to support the can J, the cylindrical stem *p*10 of the table passing out through the cylindrical stem *m*15 of the auxiliary sealing chamber M, the stem *p*10 has fixed at its bottom end a groove ring *p*9, with which engage split rings *p*15 connected by pins *p*16 to opposite sides of a bow-shaped lever *p*8 pivoted at *p*7 to a fixed bracket, and connected to a lever *p*6 with which a cam roller *p*5 on the transmission member *p*3 engages. The member *p*3 is guided in a fixed guide *p*4 and has a roller *p*2 actuated by a cam *p*1 on the shaft D. A spring *p*22 is inserted between the table K and the groove ring *p*9 and tends to return the movable table P to its lower position.

A port *v*1 (see Figs. 2 and 3) is formed in the bottom *c*15 of the main sealing chamber C which port leads to the opening *c*13, at a point below the shutter valve H, the other end of the port *v*1 leads to a port *v*2 in the casing *v*3 of a rotary valve V (see Fig. 4). The ports *v*1 and *v*2 form a passage-way opening into the aperture *c*13.

The casing has two further ports *v*4 and *v*5, the port *v*1 being connected by a pipe *v*7 to the suction side of an exhausting pump Q, and the port *v*5 leading by a pipe *v*8 to the suction side of a gas transfer pump S, the delivery side of which is connected by the pipe *v*9 to an inlet *v*10 to the main sealing chamber C.

The valve V is adapted to rotate in the casing *v*3 in gas-tight manner; the periphery of the valve plug in cross-section, is of D-shape so that it is adapted in one angular position to connect

the port *v*2 to the port *v*4, whilst it closes the port *v*5 and in another angular position to connect the port *v*2 to the port *v*5 whilst maintaining the port *v*4 closed.

The plug of the valve V is fitted with a port *v*6 which when it aligns with the port *v*2, and only then, connects the port *v*2 momentarily with the atmosphere through a port *6a* in the valve casing cover *6b*.

The valve is fitted with a stem *v*11 journalled in an extension *v*12 carried from the valve casing, to the end of which stem a bevel wheel *v*13 is fitted, which gears with the bevel wheel *v*14 mounted on a shaft *v*15 journalled in a fixed bracket *v*16, to the other end of which shaft *v*15 a bevel wheel *v*17 is fixed which gears with a bevel wheel *v*18 carried on the cam shaft D (see Fig. 1).

It will be seen that the several parts described are operated once through one complete cycle for each revolution of the cam shaft D and, of course, the cams are set so as to give the correct sequence of operation.

The action is as follows:—

Assuming that the machine is to be employed to seam the cams whilst the interior thereof is subjected to an atmosphere of any suitable inert or preserving gas; the main sealing chamber C would be connected to any suitable source of supply of the said gas, so that its interior would be maintained charged at a suitable pressure with the said gas.

Assuming the auxiliary sealing chamber M to be in its lowermost position, in which its top edge is level with or below the top of the table K, that the moving table P is in the position shown in Figs. 1 and 4, and that a can J with its lid fitted to it, (and preferably clenched in position thereon, by means as described in U. S. patent application, Serial No. 681,996, made by me and filed July 24, 1933), has been transferred to the table P and centered thereon, and that the shutter valve H is closed;—the auxiliary sealing chamber M is raised to the position shown in Figs. 1 and 2, an air-tight joint being made between its upper end and the opening *c*13 by means of the jointing ring *m*10. At this moment the valve V will connect the port *v*1 through the ports *v*2 and *v*4, through the pipe *v*7 to the suction side of the exhausting pump Q, with the result that atmospheric air will be exhausted from both the can and the interior of the chamber M. As soon as this has been accomplished and the valve V closes the port *v*2, the shutter valve H is operated by the cam *h*1, and opens the communication between the main sealing chamber C and the interior of the auxiliary sealing chamber M, the latter and the interior of the can becoming charged with the inert gas from the main chamber C.

The table P and with it the can J will then be raised by the cam *m*1 until the can is in proper relationship with the seaming mechanism; the latter will then, by the operation of the cam *c*1, be rendered operative to seam the lid of the can in position on the can. The table P is then lowered resuming the position shown in Fig. 1, whereupon the shutter valve H is closed by the operation of the cam *h*1, and immediately thereupon the valve V rotates into the position in which it connects the port *v*1 through the port *v*2 to the port *v*5 and pipe *v*8 to the suction side of the gas pump S which thereupon withdraws the inert gas from the chamber M and returns it to the main chamber C, thus avoiding any waste of this gas. There may then be a partial vac-

uum in the chamber M, but the momentary connection of the port v2 through the port v6 restores atmosphere pressure to the chamber M.

As soon as the valve V has closed the port v2 leading through the port v1 to the auxiliary chamber M, the latter is by the operation of the cam m1, lowered to its bottom position in the well k1; the can J is then removed from and the next can to be treated is moved into place on the table 10 P, and the operations described are repeated.

Referring now to Figs. 5 and 6;—K² is the fixed table which is extended upwardly in the form of two segmental portions k20 of cylindrical configuration, the respective vertical edges of which 15 form two openings k21 and k22 of width sufficient to permit a can to be passed laterally through them; the auxiliary chamber M² is of cylindrical configuration, and is mounted within the segmental portions k20 so that its cylindrical 20 surface makes gas-tight joint therewith; the chamber M² has two openings m21 and m22 which, in one position of the chamber, as shown in Fig. 6, coincide with the openings k21 and k22.

Angular motion is imparted to the chamber 25 M² by the cam m20 mounted on a vertically disposed cam shaft D¹ arranged and driven in a manner similar to that described with reference to Figs. 1 to 4; the cam m20 engages a roller m23 on a lever m24 pivoted at m25, the end of 30 the lever being connected by a rod m26 to a lever m27 attached to the chamber M². The chamber M² in this modification has no axial motion and a permanent gas-tight joint is made between the top m28 of the chamber M² and the 35 bottom c15 of the casing C, and in order to give a continuous peripheral joint around the openings m21 and m22; these openings do not extend to the top jointing edge m28. The joint between the top of the casing M² and c15 is outside 40 the opening c13 controlled by the shutter valve H2.

The seaming head c, the rising and falling table P2 and shutter valve H2 are operated substantially as described with reference to Figs. 1 to 4. 45 The port v1 corresponds with the port v1 in Figs. 1, 3 and 4 and is connected to a valve V by which it is successively put into communication with an air exhausting pump, a gas transfer pump m9, and with the atmosphere, as described with 50 reference to Figs. 1 to 4.

The action is as follows:—

Assuming the valve H2 to be closed and the chamber M² occupies the position shown in Figs. 5 and 6, the can is introduced through one of the 55 openings k21 or k22 of the fixed cylindrical casing k20, and m21 or m22 of the chamber M², and is centred on the movable table whilst the table is in its lowermost position, the cam m20 then moves the chamber M² until the openings 60 m21 and m22 are closed by the segmental portions k20; the port v1 is then connected to an exhausting pump and the atmospheric air contained in the can and the chamber M² is exhausted; after the port v1 has been closed the 65 shutter valve H is opened by the cam mechanism and the interior of the chamber M² put into communication through the opening c13 with the interior of the main sealing casing C, and the can and chamber charged with the inert gas. 70 The table P2 is then raised so as to bring the can and its lid into operative relationship with the seaming rollers which are thereupon made operative by a cam driven from the cam shaft D¹ as described in connection with Fig. 1. When 75 the seaming process is completed the valve H2

is closed, the port v1 put into communication with the gas transfer pump by which the gas in the chamber M² is transferred to the main chamber C. After port v1 is again closed the chamber M² is moved to the position shown in Figs. 5 and 6 and the can withdrawn through the openings m21 and k21 which are then in alignment, and whilst the apparatus is in this position the succeeding can is introduced through k22 and m22 and the operations repeated. 10

In the modification illustrated in Fig. 7 there are a series of auxiliary sealing chambers M3, open at the top and closed at the bottom, suitably spaced near the periphery of a rotatable cylindrical drum m30 which is a gas-tight fit 15 in the semi-cylindrical casing c20 which is a continuation of the main sealing casing C² in which the sealing head c21 is located. The semi-cylindrical casing c20 makes gas-tight joints with the top, bottom and periphery of the drum 20 m30. The drum m30 is given a step-by-step angular movement in the direction of the arrow so that the chambers M3 are in succession brought into position within the casing c20, the top of the said casing then closing the chamber. 25

In the example illustrated there are seven equally spaced chambers M3, and each step-by-step movement given to the drum m30 is one-seventh of a complete revolution, and there is 30 a pause at the end of each step sufficiently long to enable the seaming mechanism to be operated to seam the lid on the can then in position under the seaming head.

Denoting the successive angular positions into 35 which each chamber M3 is moved, as 1, 2, 3, 4, 5, 6 and 7, and assuming that a treated can is removed when its chamber is in position 6 and a fresh can introduced at position 7, it will be seen that in position 1 a particular chamber 40 with the can in position is just about to enter the casing c20. As soon as the chamber completely enters the casing the top of the chamber is closed by the top of the casing, but in passing from position 1 to position 2 the top of the 45 chamber passes under a port v20 formed in the top of the casing, and connected to an exhausting pump, by which the atmospheric air in the chamber and the can are exhausted. In position 2 the top of the chamber is still closed by the casing c20 but as the can passes from position 2 to position 3 in alignment with the seaming head c21, the can and chamber become filled with the gas contained and supplied to the sealing chamber C². 50

In position 3 the lid is seamed on to the can.

In position 4 the top of the chamber is again closed by the casing c20 and in passing from position 4 to position 5 the chamber passes under a port v21 connected to a gas transfer pump by 60 which the inert gas in the auxiliary sealing chamber is transferred to the main sealing chamber through the port v22. In position 5 the sealing chamber passes out of the casing and between this position and position 1 the treated 65 can is removed and an untreated can inserted.

The required step-by-step movement with a pause at the end of each step is given to the drum m30 and the relative movement between the seaming head and the can in position for seaming 70 is given to the seaming head, by any suitable and well known mechanisms, for example, the drum m30 may be driven from a cam shaft through a lever fitted with a ratchet engaging a detent fixed to the drum, the relative movement between 75

the can and the seaming head and movement of the seaming rollers into operative position being given by any suitable and known cam mechanism operated by the same cam shaft.

5 In the modification shown in Figs. 8 and 9 the arrangement is similar to that last described except that the casing $c21$, which is an extension of the sealing chamber C , is carried almost around the periphery of the drum $m31$, and that the 10 auxiliary sealing chambers $M4$ (of which four are shown) formed in the drum may be closed at the top by the part $m32$ and at the bottom by the part $m33$ but have open fronts $m34$. When a chamber $M4$ is in position 1 opposite the opening 15 $c22$ in the casing $c21$ the can J is introduced. A step-by-step movement is given to the drum $m31$, the first step of which brings the chamber $M4$ into position 2, where a port $v23$ in the top of the chamber is brought into alignment with a 20 port $v24$ in the cover $c23$ of the casing, which port $c23$ communicates with the suction side of an exhausting pump so that air is withdrawn from the chamber and the can; the next movement brings the chamber into position 3; the can 25 is now, by any suitable mechanism, for the purpose well known to those skilled in the manufacture of such machines, moved out of the chamber $M4$ to the position 3^a in vertical alignment with the seaming head $c30$ carried in the sealing chamber $C3$. The can is then filled with the inert gas contained by the chamber $C3$, and is sealed by operating the seaming head $c30$, whereupon the can is moved by said mechanism back to a chamber $M4$ in position 3, which chamber is then carried to position 4 where the port $v23$ is brought opposite the port $v24$ connected to a gas transfer pump which exhausts the gas from the chamber $M4$ and transfers it through the port $v26$ to the main sealing chamber $C3$. 30 The next step brings the chamber back to position 1 where the treated can is withdrawn and an untreated can introduced into the chamber.

The arrangement shown in Fig. 10 is substantially similar to that described in connection with Figs. 8 and 9 except that there are two enclosing parts $c24$ of the casing $C4$ and two drums $m40$ and $m41$ each having four chambers $M5$. The chambers are open at the front $m42$ and the casings $c24$ have an opening $c25$ at the front.

50 The port $v30$ in the part of the casing enclosing the drum $m40$ and the port $v32$ in the part enclosing the drum $m41$ lead to an exhausting pump; and the port $v31$ in the part of the casing surrounding the drum $m40$ and the port $v33$ in 55 the part of the casing enclosing the drum $m41$ lead to the suction side of a gas transfer pump, the delivery of which is connected to the port $v34$ in the casing C .

Assuming the apparatus to be in the position 60 shown in Fig. 10 and that a can has been introduced into one of the chambers $M5$ in the drum $m40$, when the said chamber passes from position 1 to position 3 it would with the contained can, on passing the port $v30$ in position 2, be exhausted of atmospheric air, when the chamber reaches position 3 it opens into the interior of the casing $C4$ filled with the inert gas, the can and chamber are charged with this gas.

By a suitable mechanism well known to those 70 skilled in the manufacture of such machines, the can is withdrawn from the chamber $M5$ when it is in position 3, and the can is moved to position 3^a in axial alignment with the seaming head $c26$, and after being seamed is, by the same mechanism, moved into a chamber $M5$ in the drum

$m41$ occupying the position 3. The chamber $M5$ is then moved in the direction of the arrow opposite the port $v33$ through which the gas transfer pump withdraws the gas in the auxiliary chamber $M5$ and transfers it to the main chamber $M5$ in drum $m41$ through port 34 , so that when the chamber $M5$ in drum $m41$ reaches position 1 atmospheric air is admitted and the can withdrawn; the chamber $M5$ in the drum $m40$ which was in position 3 when the can was removed from it, will move in the direction of the arrow, and when passing the port $v31$ the inert gas in the said chamber $M5$ will be withdrawn and transferred to the main casing.

Having now fully described my invention I declare that what I claim is:—

1. In apparatus for sealing containers in a gas other than atmospheric air, in combination;—a main sealing chamber, the interior of which is maintained charged with the said gas and cut off from the atmosphere; sealing means located within the main chamber; a vacuum pump; a gas transfer pump; the delivery side of which is connected to the interior of the main chamber; an apertured auxiliary sealing chamber; means to move the auxiliary chamber from a position in which it is open to the atmosphere and an unsealed container introduced, to a position in which its interior is cut off from the atmosphere and connected to the vacuum pump suction; means to connect the interior of the auxiliary chamber to the interior of the main sealing chamber; means to present the container to the sealing means; means to operate the latter to effect the sealing; means to disconnect the auxiliary chamber from the main chamber; means to close the auxiliary chamber and to connect its interior to the suction side of the transfer pump; and means to return the auxiliary chamber to the position in which its interior is open to the atmosphere.

2. Apparatus for sealing containers in a gas other than atmospheric air, in combination;—a main sealing chamber, the interior of which is continuously cut off from the atmosphere and maintained continuously charged with said gas, said chamber having an aperture with an external facing, and a passageway through the wall of the aperture; a container-sealing device located in the main sealing chamber; means for operating the sealing device; a vacuum pump; a gas transfer pump, the delivery of which is connected to the interior of the main sealing chamber; a valve adapted to close the aperture; means for operating the said valve; a multiple-way rotary valve fitted to the said passageway adapted cyclically to connect the passageway in succession to the suction of the vacuum pump, and to the suction of the gas transfer pump; means for driving the rotary valve; an open-topped auxiliary sealing chamber; means for moving the auxiliary chamber between two positions, an upper position in which its open top surrounds the said aperture and makes joint with the aperture facing, and a lower position in which its open top is below the said facing by a distance slightly greater than the height of the tallest container to be sealed; a table axially movable within the auxiliary chamber; means for moving the table between a lower position in which a container can be located on it, and an upper position in which it moves the container on it into operative relationship with the sealing means.

3. Apparatus for sealing containers in a gas other than atmospheric air, in combination;—a

main sealing chamber, the interior of which is continuously cut off from the atmosphere, and maintained continuously charged with said gas, said chamber having an aperture with an external facing, and a passage-way through the wall of the aperture; a container-sealing device located in the main sealing chamber; means for operating the sealing device; a vacuum pump; a gas transfer pump the delivery of which is connected to the interior of the main sealing chamber; a valve adapted to close the aperture; means for operating the said valve; a multiple-way rotary valve fitted to the said passage-way adapted cyclically to connect the passageway in succession to the suction of the vacuum pump, and to the suction of the gas transfer pump; means for driving the rotary valve; a rotatable cylindrical auxiliary chamber having a lateral aperture and the open top of which makes fluid-tight joint with the facing of the aperture in the main chamber, a fixed cylindrical casing fitting the external cylindrical surface of the auxiliary chamber and having a lateral opening; means for producing relative angular movement between the auxiliary chamber and the said casing from the angular position on which the lateral aperture in the chamber aligns with the lateral aperture in the casing, to a position in which its said lateral aperture in the auxiliary chamber is closed by the casing; a table axially movable within the auxiliary chamber; means for moving the table between a lower position in which a container inserted through the lateral openings can be located on it, and an upper position in which it moves the container on it into operative relationship with the sealing means.

4. In apparatus for sealing containers in a gas other than atmospheric air, in combination;—a main sealing chamber, the interior of which is continuously cut off from the atmosphere and maintained continuously charged with the said gas said main sealing chamber having a rectangular aperture through which the containers are introduced and withdrawn; an ante-chamber, the walls of which are formed by two sides, a top and a bottom extending respectively exteriorly from the sides, top and bottom of the said aperture, the inside faces of the said sides of the ante-chamber being of cylindrical configuration and the wall thereof having two oppositely disposed through ports; a drum rotatably mounted in relation to the sealing chamber, with a portion thereof in the sealing chamber and a portion thereof outside the ante-chamber, the cylindrical surfaces of the intermediate portion of the drum making a fluid-tight joint with the inside cylindrical portions of the sides of the ante-chamber, and the top and bottom of the said intermediate portion making fluid-tight joint with the insides of the top and bottom of the ante-chamber, said drum having formed in it and near its cylindrical periphery a series of circumferentially spaced open-topped recesses to form auxiliary sealing chambers which, by a step-by-step angular movement imparted to the drum, are moved from a position in which they are open to the atmosphere into a position in which they are open to the interior of the main sealing chamber; sealing means located in the main sealing chamber; means for driving and operating the sealing means; one of the above mentioned ports in the wall of the ante-chamber communicating with each auxiliary chamber in succession after the latter has entered the ante-chamber, before it opens into the main chamber and whilst

it is closed by the wall of the ante-chamber; the other port in the wall of the ante-chamber communicating with each auxiliary chamber in succession after the latter has passed through the main chamber and entered the other section of the ante-chamber and whilst it is closed by the wall of the ante-chamber; a vacuum pump, the suction side of which is connected to the first mentioned port; a gas transfer pump, the suction side of which is connected to the second mentioned port, and the delivery side of which is connected to the main sealing chamber.

5. In apparatus for sealing containers in a gas other than atmospheric air, in combination;—a main sealing chamber, the interior of which is continuously cut off from the atmosphere and maintained continuously charged with the said gas; sealing means located in the main sealing chamber; an ante-chamber of cylindrical configuration closed at the top and bottom and having two apertures in its cylindrical portion, the peripheral portion of one opening making joint with the peripheral portion of an opening into the main sealing chamber, and the other oppositely located aperture opening into the atmosphere, said ante-chamber having two oppositely located ports in its wall; a drum rotatably mounted in the ante-chamber, the cylindrical and end surfaces of which make fluid-tight joint with the corresponding surfaces of the ante-chamber, said drum having formed in its cylindrical periphery equally spaced recesses forming auxiliary sealing chambers which by a step-by-step angular movement of the drum are moved from an initial position in which they are in alignment with the last mentioned aperture through which an unsealed container is introduced, to a position in which they are closed by the walls of the ante-chamber, and thence into a position in which they open to the main sealing chamber, thence to a position in which they are closed by the walls of the ante-chamber, and thence to the initial position; one of the above mentioned ports communicating with an auxiliary sealing chamber when the latter has been moved from its initial position to a position in which it is otherwise closed by the walls of the sealing chamber, the other said port opening into a sealing chamber after the latter has passed the opening into the main sealing chamber and whilst it is otherwise closed by the walls of the ante-chamber; a vacuum pump, the suction of which is connected to the first mentioned port; a gas transfer pump, the delivery side of which is connected to the main sealing chamber, and the suction of which is connected to the second mentioned port.

6. Apparatus for sealing containers in a gas other than atmospheric air as claimed in claim 5, with an additional and oppositely located like ante-chamber and rotating drum.

7. A machine as claimed in claim 2, in which the sealing head is driven by a horizontal driving shaft, the driving means passing in fluid-tight manner out of the main sealing chamber, and in which the operation of the sealing means is effected by a slideable cam-operated member passing in fluid-tight manner through the wall of the sealing chamber, and in which the shutter valve, the auxiliary sealing chamber, and the table are reciprocated by respective cams located on a vertical cam shaft driven at the appropriate speed by the horizontal driving shaft and geared to the rotary valve.

8. A machine as claimed in claim 2, in which a shutter valve fitted to the aperture in the main

sealing chamber is operated by a cam-operated horizontally slidable member which imparts motion to the short arm of a lever on a fixed pivot, to the long arm of which the valve is connected by a link.

5. Apparatus as claimed in claim 2, in which

the rotary valve is a three-way valve adapted to connect the passage-way in the wall of the aperture of the sealing chamber cyclically in succession to the vacuum pump suction, the gas transfer pump suction and to the atmosphere.

FRANK OSCAR LEVI CHORLTON.
